UNITED STATES PATENT OFFICE

CHARLES G. MANZ, OF NEW KENSINGTON, PENNSYLVANIA.

SKELETON LID.

1,207,586.

Specification of Letters Patent.

Patented Dec. 5, 1916.

Application filed October 15, 1915. Serial No. 55,924.

To all whom it may concern:

Be it known that I, CHARLES G. MANZ, a citizen of the United States, residing at New Kensington, in the county of Westmoreland and State of Pennsylvania, have invented certain new and useful Improvements in Skeleton Lids, of which the following is a specification.

This invention relates to skeleton lids designed for use in connection with the burners of gas or oil burning stoves and may be more properly termed an economy lid, as it is designed to confine the flame as well as the fumes in such manner that they will be concentrated upon the utensil or other receptacle which the lid supports.

The main object of my invention resides in a construction of collar member attachably mounted in connection with the lid proper and depending in such manner as to encircle the gas burner.

In this connection, it is also an object of my invention to so construct the lid that a plurality of sets of flanges are provided, in connection with any of which the depending collar may be used to increase or decrease its diameter, as may be desired.

A further object of my invention resides in so constructing the lid that adjustments are provided whereby this lid may be adapted to various sizes of stove hole openings, it being desirable to provide these adjustments in order to prevent shifting back and forth of the skeleton lid.

The preferred embodiment of my invention is shown in the accompanying sheet of drawings, in which similar characters of reference designate corresponding parts, and in which:

Figure 1 is a partial plan view of my improved type of lid, Fig. 2 is a side elevation of the structure shown in Fig. 1 with a portion of the collar broken away, and, Fig. 3 is a bottom view of the structure shown in Fig. 2.

In these several views, the lid itself is formed of a general framework, this general framework comprising a circular frame piece 1 and a plurality of radially inwardly extending fingers 2, which latter may be connected with each other for purposes of stability as is shown at 3. These fingers all extend inwardly a distance to leave an open space such as shown at 4 adjacent their extreme inner ends. The underside of the general framework is also provided with a plu-

rality of depending segmental flanges arranged in sets, the flanges designated 5 being disposed at a point nearer the center of the lid as a whole than those designated 6. 60 Co-operatively mounted in connection with these flanges is a depending collar 7, which collar is preferably of ribbon nature formed to assume the shape of a circle as is shown in the drawings, the overlapping ends of this 65 ribbon being shown at 8. This collar comprises an outside metal base member 9 whose upper and lower edges are turned over as is shown at 10 to securely clamp layers of asbestos 11 or other similar material between 70 them. This collar is securely held in position with either set of flanges by means of the wires shown at 12, these wires being of sufficient stiffness, so that when their ends are turned over as is shown at 13, a secure 75 grip will be had.

The circular member 1 is formed with a series of radially arranged slots, such as are shown at 14, the opposing walls of these slots being serrated after the manner shown 80 at 15. In order that the lid itself may be adapted to various sizes of stove openings, I have made these serrations of a size to receive the shanks of bolts shown at 16 and because of their size it is impossible for them 85 to slide back and forth within the slots except after having completely withdrawn them. In order to prevent their dropping out of position, nuts 17 are threaded on their lower ends and moved into clamping engagement as is shown. These nuts then serve as 90 the centering means to hold the lid as a whole centered within the stove openings.

From the above description, it will be 95 apparent that the collar member 7 may be adjusted to assume various diameters since this collar member may be bent to coöperate with either the inside or outside depending faces of either of the flanges 5 and 6, whereupon four different sizes will be 100 attained. Also, this collar depending and encircling the gas burner will confine all of the fumes and flames to concentrate them on the under surface of any receptacle placed on top of the lid. Finally, by means 105 of the adjustment created by the bolts 16, the lid may be adapted to various sizes of stove openings and in this manner the lid itself held properly centered both with respect to the gas burner and with respect to 110 the stove opening.

An inspection of Figs. 1 and 2 will show

that the radially arranged fingers 2 are extended to a point slightly above the upper face of the circular frame piece 1, this arrangement being resorted to in order to 5 permit the escape of the products of combustion and also to permit the flames to extend out through these openings should they burn with sufficient intensity.

What I claim, is:

- 10 1. In a skeleton lid for gas burners, a general ribbed framework, and adjustable means carried by said framework to fit it to the desired stove opening.
- 15 2. In a skeleton lid for gas burners, a general ribbed framework, said framework being provided with a plurality of radially arranged slots whose radial walls are serrated, and a bolt and nut in each of said slots, said bolts fitting said serrations and 20 forming the means for adjusting the lid to make it fit the desired stove opening.
- 25 3. In a skeleton lid for gas burners, a general ribbed framework, a collar depending from the underside of said framework designed to encircle a gas burner, and adjustable means carried by said framework to fit it to the desired stove opening and at the same time locate said collar concentrically 30 with the gas burner whether the burner is concentric with the stove opening or not.
- 35 4. In a skeleton lid for gas burners, a general ribbed framework, a plurality of flanges depending from the underside of said framework, an attachable expandible depending collar designed to encircle the gas burner and be attached to assume various sizes by means of said flanges, and means for attaching said collar to any of said flanges.
- 40 5. In a skeleton lid for gas burners, a

general ribbed framework, a plurality of flanges depending from the underside of said framework, an attachable expandible depending collar designed to encircle the gas burner and be attached to assume 45 various sizes by means of said flanges, means for attaching said collar to any of said flanges said framework being provided with a series of radially arranged slots, and a bolt and nut in each of said slots adjustable to 50 assume any desired position to fit the lid to the desired stove opening.

6. In a skeleton lid for gas burners, a general ribbed framework, a plurality of flanges depending from the underside of the 55 framework at different distances from its center, a ribbon designed to be bent to circular shape to coöperate with any of said flanges, and means for holding said bent ribbon in connection with the flanges with 60 which it coöperates.

7. In a skeleton lid for gas burners, a general ribbed framework, a plurality of flanges depending from the underside of the framework at different distances from its 65 center, a ribbon designed to be bent to circular shape to coöperate with any of said flanges, means for holding said bent ribbon in connection with the flanges with which it coöperates, said framework being 70 provided with a series of radially arranged slots, and a bolt and nut in each of said slots adjustable to assume any desired position to fit the lid to the desired stove opening.

In testimony whereof I affix my signature 75 in presence of two witnesses.

CHARLES G. MANZ.
